CLAIM

The ornamental design for a bottle with bottom cup, as shown and described.

DESCRIPTION

FIG. 1 is a top right perspective view of a bottle with bottom cup showing my new design;

FIG. 2 is a bottom left perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top plan view thereof; and,

FIG. 8 is a bottom plan view thereof.

The broken lines immediately adjacent to the shaded areas represent an unclaimed boundary between claimed and unclaimed surfaces while all other broken lines represent unclaimed subject matter. None of the broken lines form any part of the claimed design.
